UNITED STATES PATENT OFFICE

EWALD F. TOBOLD, OF CLEVELAND, OHIO, ASSIGNOR TO THE DILL MANUFACTURING COMPANY, OF CLEVELAND, OHIO, A CORPORATION OF OHIO

QUICK-DETACHABLE DUSTCAP

Application filed April 18, 1927. Serial No. 184,479.

The present invention relates to dust caps of the type and kind which are adapted to be associated with the valve stem of a pneumatic tire or other pneumatic device.

5 One of the objects of the invention is to provide a construction in which the dust cap may be quickly attached and detached from the valve stem without the necessity of turning the dust cap along the entire threaded 10 stem, as is customary with the usual type of dust cap, in which the dust cap is provided with a threaded portion at the open end of the cap.

15 A further object of the invention is to provide a means associated with the shell of a dust cap by which means the shell of the dust cap is fitted to the valve stem by an expanding action of the attaching means when the dust cap is mounted upon the end of the valve 20 stem.

25 A further object of the invention is to provide a device, of the character described, in which the attaching means is formed from sheet metal by a stamping operation, whereby there is produced an attaching means at a low cost of manufacture.

30 Other objects of the invention will appear as the description proceeds.

Reference should be had to the accompanying drawing in which:

Fig. 1 is an elevation showing a dust cap embodying the present invention;

Fig. 2 is a sectional plan view on the line 2—2 of Fig. 1;

35 Fig. 3 is a sectional plan view on the line 3—3 of Fig. 1; and

Fig. 4 is a sectional elevation showing in detail certain features of construction.

40 Referring to the drawing, 1 indicates the shell of a dust cap, which dust cap is preferably formed so as to have a plurality of flat side faces as indicated at 2.

45 At the upper end of the dust cap there is provided an extension 3 in which is formed a transverse slot 4 which serves as a screw driver member by which valve insides, which are customarily mounted within the valve stem, may be inserted and removed.

50 The valve stem, in which the device is adapted to cooperate, is indicated at 5, and is

of the usual construction having the outer end of reduced diameter, and threaded, as indicated at 6.

Within the shell 1 is what I would term 55 an attaching member which is so called because it serves to form an attachment between the shell of the dust cap and the valve stem when the attaching means is secured upon the end 6 of a valve stem. This attaching member is generally represented at 7.

The attaching member is formed with a 60 central body portion 8, which is interiorly threaded, and also forming a part of the member 7 are a plurality of resilient fingers 9. These resilient fingers at their outer ends 65 are formed with an inwardly extending shoulder 10, and with outwardly extending portions 11.

The construction which has so far been 70 described may readily be formed from sheet metal by a stamping process, in which a portion of the sheet metal is formed with an 75 upstanding flange forming the body portion 8 and the fingers 9 are also stamped out of the blank sheet of metal and bent into the position in which they are shown in Figs. 1 and 4.

The arrangement of the parts is such that 80 when the device, just described, is inserted within the shell of a dust cap the resilient fingers 9 are in frictional engagement with the wall of the shell, the friction being sufficient to retain the attaching member in any adjusted position within the shell and, yet, the attaching member may be moved within the 85 shell by a sliding action.

An expanding member 12, which is preferably cylindrical in shape, is mounted within the fingers 9 and is of such diameter that it is normally retained within the resilient fingers 9 by the inturned portions 10 of the resilient fingers. In other words, the diameter 90 of the expanding member 12 is slightly greater than the distance between the inturned portions 10 of oppositely disposed fingers 9. 95 This expanding member 12 is formed of sheet metal and has a depending flange 12^a so that the general structure of the member 12 may be described as cup-shaped. This member 12 is formed with a central dome-shaped por- 100

tion 12^b for a purpose which will be presently described.

Within the member 12 there is a sealing member, the function of which is to seal the end of the valve stem so as to prevent the escape of air which might occur incident to air leakage of the valve insides. The sealing member also has an additional function, namely, that of causing the member 12 to be pushed upwardly or outwardly when the sealing member comes into engagement with the end of a valve stem. The sealing member, which is generally indicated at 13, is cup-shaped and has a flange 14 and dome-shaped portion 15.

Within the member 13 there is a molded rubber body which is indicated at 16. This molded body substantially fills the cup-shaped member 13 but the central portion thereof is recessed, as indicated at 17, so as to provide a clearance space for the upper end of the small valve stem of the valve insides which frequently extends a slight distance beyond the end of the valve stem. Obviously, it is desirable to provide clearance for the small valve stem so as not to depress the same when the dust cap is mounted on the end of the valve stem.

The dome-shaped portion 15 of the member 13 is of a slightly less radius than the dome-shaped portion 12^b of the expanding member, so that when the dome-shaped portion 15 engages with the dome-shaped portion 12 there is a limited surface engagement which will permit relative movement between the expanding member 12 and the member 13. In fact, the intention is that the member 13 shall be of such dimensions as to readily move with respect to the member 12 and the two members 12 and 13 may have a swivel action with respect to each other.

When the dust cap with the attaching member, which has been described, is inserted over the end of a valve stem, the threaded portion of the part 8 will engage with the threads on the end 6 of the valve stem and a rotary movement will cause part 8 to travel along the threads of the valve stem. The end of the valve stem 6 will engage with the rubber portion of the sealing member 13 and as rotation of the part 8 is continued the member 13 will push outwardly upon the expanding member 12. This outward movement of the part 12 will cause the same to engage with the inturned portion 10 of the fingers 9 and press these fingers outwardly, particularly the portions 11 of said fingers, into engagement with the inner wall of the shell 1. The frictional engagement is very pronounced, in fact so pronounced that the shell is effectively held from movement and so is, in effect, attached to the valve stem 5.

It will be apparent from the foregoing description that it requires only a few turns of the portion 8 upon the end of the valve stem

6 to accomplish the desired result, so that the dust cap may be quickly attached and quickly detached from the valve stem.

It will be apparent that when the rubber portion 9 of the sealing member has engaged with the end of the valve stem 6, it is quite essential to obviate rotation between the rubber portion and the end of the valve stem, because such rotation would tend to wear and destroy the rubber. However, inasmuch as the dust cap and the attaching means must be rotated in order to secure attachment, the swivel action between the sealing member 13 and the expanding member 12 is provided so that the two parts mentioned may turn or swivel with respect to each other, thus permitting free rotating action in attaching or detaching the dust cap, and at the same time avoid destructive results with respect to the sealing member.

One of the important features of this invention lies in the fact that the attaching member 7, comprising the portions 8 and the fingers 9, may be readily formed from sheet metal by the use of dies. Further, the expanding member 12 may be readily formed from sheet metal and the cap portion 13 of the sealing member may also be formed of sheet metal.

This will obviate the making of these parts from solid bar metal by the screw machine process and thereby greatly lower the cost of production.

The matter of providing a dust cap construction at a low cost of manufacture is important because such structures, as herein described, are competitive with respect to the ordinary form of dust cap which, as is well known, comprises a shell closed at one end and open at the other end with the inner portion of the shell at the open end provided with screw threads. Such devices readily perform the function of protecting the end of valve stems but have the disadvantage of requiring considerable time in the mounting and unmounting of such dust caps from the valve stem, due to the fact that they must be screwed along the entire body portion of the valve stem.

The quick detachable dust cap herein disclosed has a decided advantage over the old form in the matter of the quickness of attaching and detaching, and also in the matter of more positive holding, but nevertheless it is imperative that the cost of manufacturing quick detachable dust caps shall not be too great over the cost of manufacturing the ordinary plain dust cap.

Having thus described my invention, I

1. A dust cap construction comprising a shell which is closed at one end and open at the other end, an attaching member within said shell having a body portion which is adapted to be mounted upon the end of a

valve stem, a plurality of upturned resilient fingers carried by the body portion, a cup-shaped member encircled by the said resilient fingers, a sealing member mounted within said cup-shaped member and free to turn with respect thereto, said fingers having portions adapted to be engaged by the said cup-shaped member to move them outward when the attaching member is mounted upon the end of a valve stem.

2. A dust cap construction comprising a shell which is closed at one end and open at the other, attaching member within said shell and adapted to be attached to the end of a valve stem, a plurality of upturned resilient fingers carried by the body portion, a cup-shaped expanding member encircled by the said fingers, a sealing member comprising a cup-shaped portion adapted to fit within the expanding member and to have relative movement with respect thereto, a packing material within the last cup-shaped member adapted to engage the end of a valve stem, the said fingers having means engaged by the said expanding member to move the fingers outwardly when the attaching member is secured upon the end of a valve stem.

3. A dust cap construction comprising a shell which is closed at one end and open at the other end, an attaching member within said shell having a body portion with a threaded opening adapted to engage with the end of a valve stem, a plurality of upturned resilient fingers carried by the body portion, an expanding member encircled by the said fingers, a sealing means associated with the said expanding member and capable of relative turning movement with respect to the expanding member, the said resilient fingers having means adapted to be engaged by the expanding member to move them outwardly when the attaching member is mounted upon the end of a valve stem.

In testimony whereof, I hereunto affix my signature.

EWALD F. TOBOLD.
